Fig. 2

Fig. 3

Fig. 4

FIG. 1 is a perspective view of a tire showing my new design, it being understood that the tread design is repeated throughout the circumference of the tire as shown schematically by solid lines, the opposite side being substantially the same as that shown.

FIG. 2 is a fragmentary top plan view thereof.

FIG. 3 is a fragmentary side elevational view thereof.

FIG. 4 is a sectional view thereof taken along the line IV-IV in FIG. 2.

I claim:

The ornamental design for a tire, as shown and described.
